(57) **CLAIM**

The ornamental design for a bin, as shown and described.

DESCRIPTION

FIG. 1 is a perspective view of a bin according to the invention.

FIG. 2 is a front elevational view of the bin.

FIG. 3 is a rear elevational view of the bin.

FIG. 4 is a right side view of the bin.

FIG. 5 is a left side view of the bin.

FIG. 6 is a top plan view of the bin; and,

FIG. 7 is a bottom plan view of the bin.

The portions shown in broken lines form no parts of the claimed design.
